UNITED STATES PATENT OFFICE

2,031,702

SILENCER FOR INTERNAL COMBUSTION ENGINES

Kurt Frey, Oranienburg, near Berlin, Germany,
assignor to Degea Aktiengesellschaft (Auer-
gesellschaft) Berlin, Germany, a corporation of
Germany

Application January 9, 1935, Serial No. 970
In Germany March 26, 1934

2 Claims. (Cl. 137—160)

It is well known that felt or cotton-wool like inorganic materials, such as glass cotton-wool or slag-wool, possess a high sound-absorbing property. This property has already been utilized 5 also for the silencing or damping of the noise of the exhaust in internal combustion engines. For that purpose the exhaust gases were caused either to pass along some surfaces lined with material of that kind, or they were led through filters consisting of such materials. In the former case the muffling of the sound is not particularly good, in 10 the latter instance an increase of the resistance will take place, which in turn will cause a reduction of the efficiency of the motor. At the same time there is the danger of obstruction through 15 soot and oil fumes.

It has now been ascertained that a way may be chosen between these two extreme cases, which will result in an arrangement, which will produce 20 an extraordinarily efficient silencing effect and a very slight reduction of the efficiency of the motor.

The sound absorbing felt or cotton-wool like material is formed into filling corpuscles, which latter are then wrapped in a wire-netting for the sake of support and in order to avoid the possibility that the material will loose its shape 25 through the vibrations of the silencer during the driving and through the percussive action of the exhaust. These corpuscles, which may be of any desired form (circular, cylindrical and perhaps also tube-like) and which may be of entirely different dimensions according to the size of the silencer, which again is dependent on the motor power, are accommodated within a tube of an arbitrarily large and shaped cross-section between two perforated plates in such a manner that they will become stable towards shaking. The exhaust gases will pass through the inter- 30 stices between the individual filling corpuscles.

The sound is perfectly absorbed by said fillers, and the gases will no longer leave the silencer by jerks, since they are compelled to pass between the numerous branches of the said fillers, but they will pass out in a uniform steady flow and 35 perfectly without any noise.

A preferred construction of the invention is shown in the drawing by way of example.

Referring to the drawing, *a* designates a silencer having perforated plates *b*, and *c* respectively. 10 The spherical fillers *d* are surrounded by wire netting *e*, or in other words are each enclosed within a foraminated fire-proof container *e*.

I claim:

1. A silencer for internal combustion engines 15 comprising a tube of predetermined cross-section having an inlet and an outlet, two perforated plates arranged within said tube in spaced relation to each other, a plurality of filling bodies of inorganic fibrous sound-absorbing material 10-20 located within said tube between said plates, said filling bodies being of predetermined shape to provide interstices between adjacent bodies, and individual foraminated fire-proof containers each independently enclosing one of said filling bodies 25 to substantially preserve the predetermined shape thereof.

2. A silencer for internal combustion engines comprising a tube of predetermined cross-section having an inlet and an outlet, two perforated 30 plates arranged within said tube in spaced relation to each other, a plurality of filling bodies of sound-absorbing slag-wool located within said tube between said plates, said filling bodies being of predetermined shape to provide interstices 35 between adjacent bodies, and individual wire-netting containers each independently enclosing one of said filling bodies to substantially preserve the predetermined shape thereof.

KURT FREY. 40
